UNITED STATES PATENT OFFICE

RALPH R. ROEMER, OF CLEVELAND, OHIO

COLUMN CLAMP

Application filed November 1, 1929. Serial No. 403,932.

This invention relates to clamping devices used with molding apparatus and particularly relates to column clamps for clamping molds used in the forming of concrete columns.

One of the objects of this invention is to provide a column clamp which will be cheap to construct and assemble and efficient in operation.

10 Another object is to provide a column clamp requiring the minimum number of parts and adapted to be installed in position on a column mold with the minimum number of movements by the operator thereof.

15 Another object is to provide a column clamp of improved construction in which this clamp action may be effected by the operation of driving a wedge or wedges.

Another object is to provide a column 20 clamp comprising two pairs of hinged clamping members adapted to be locked together and clamped around the column form with which it is adapted to be used by the simple operation of driving a wedge or wedges 25 through the hinged clamp elements directly without the use of any intermediate or auxiliary appliances.

Another object is to provide a column 30 clamp employing wedges provided with improved means for insuring that the wedges, when it is desired to use them, will be in a preselected position convenient to the hand of the operator.

Another object is to provide a column 35 clamp unit, two of which identical units may be employed to constitute a clamp of the class described.

Other objects will be apparent to those 40 skilled in the art to which my invention pertains.

This invention is fully disclosed in the following description taken in connection with the accompanying drawing, in which:—

45 Fig. 1 is a plan view of a column clamp embodying my invention showing the clamp in position around a column form, and with wedges which I may employ omitted to simplify the drawing;

50 Fig. 2 is a fragmentary perspective view of

the column clamp of Fig. 1 showing the wedges in clamping position;

Fig. 3 is a perspective view of one of a pair of column clamp units composing the column clamp and showing the wedges therefor in the position which they occupy preparatory to installing the clamp on the form; 55

Fig. 4 is a side sectional view of a column clamp showing the engagement of a wedge with other parts thereof; 60

Fig. 5 is a view of one of the column clamp units shown in the other figures and collapsed or folded up to compact size for transportation purposes.

As will be understood from the following 65 description, the column clamp of my invention is generally employed in pairs of units. Each one of the similar clamp units of the pair comprises a single element 1 and a double element 2 hinged together as at 3. The 70 single element 1 may be made from a bar 6 of metal, preferably steel, provided with two rows of elongated perforations 4, 4 and 5, 5, respectively. The series of perforations 4, 4 are staggered with respect to the perforations 5, 5. 75

The double element 2 is preferably made from two flat bars 7 and 8 similar to the bar 6. The bars 7 and 8 are each provided with a double row of elongated perforations 9, 9 and 10, 10; and the perforations 9, 9 are staggered with respect to the perforations 10, 10 and the perforations 9 and 10 in the bar 7 are aligned with corresponding perforations in the bar 8 in such manner that a wedge or 80 the like, which I employ, may be inserted in one of the perforations, say a perforation 9 in the bar 7 and may be passed on into and through a perforation 9 aligned therewith in the bar 8, as shown in Fig. 4. 85

The single bar 6 and the double bar 7—8 thus provided are pivotally connected together at one end of each thereof by a bolt or rivet 3 passed through suitable perforations therein. At the opposite end of the double element 2, the two bars 6 and 8 are rigidly connected together by an intermediate plate or block 11 by suitable bolts or rivets 12 passed through the parts 6, 8 and 11 above described. To further brace the two bars 6 95 100

and 8 and to hold them suitably in spaced relation, a block 13 is provided between the bars 6 and 8 and riveted or bolted thereto as by rivets 14, the block 13 being situated between the pivot 3 and the first one of the perforations 9 or 10.

The space between the bars 6 and 8 thus provided is preferably made the same thickness or slightly of greater thickness than the thickness of the bar 6, so that the latter may be folded therein between when desired and as illustrated in Fig. 5. To facilitate compactly folding the bars together in this manner, the block 13 is made to extend only part 15 way across the width of the bars 6 and 8 between which it lies.

In the operation of the clamp, I employ a pair of wedges 16 and 17 in connection with each one of the pair of column clamp units. 20 The wedges 16 and 17 are each connected by a chain 18 to a carrier 19, the chains 18 being connected to the wedges 16 and 17 by rings 22 linked in perforations 23 in the wedges and being connected with the carrier 19 by 25 rings 21 linked in perforations 20 in the carrier 19. The carrier is preferably made of flat metal and extends transversely through the space between the bars 7 and 8 and the perforations 20 are provided in the opposite 30 ends of the carrier 19.

In the operation of my improved column clamp, above described, a clamp unit is first picked up with the parts in position shown in Fig. 3, so that by the action of gravity the 35 wedge carrier slides down to the lower free end of the double element 2 carrying the wedges with it. The clamp unit is then tipped up into a horizontal plane and applied to one corner of the mold as shown in Fig. 1. The 40 other of the pair of column clamp units is handled in the same manner, if necessary by another operator, and as the two clamp units are thus put in position on the form, the single 45 element 6 of each clamp unit is inserted in between the two bars 7 and 8 of the other clamp unit. The condition of the parts thus applied to the mold is shown in Figs. 1 and 2.

The operator then takes one of the wedges and places it in a suitable perforation of the 50 single bar 6 and takes the other wedge and inserts it through suitable aligned perforations in the bars 7 and 8 and drives them home with a hammer, thus drawing the single bars farther into the double bars and 55 drawing the double bars farther in along the single bars and contracting the pair of clamp units tightly around the form in a manner that will be understood. In this connection it may be observed that the rings 22 60 are of large enough diameter to drop down over and to clear the large end of the wedge as shown at 24 in Fig. 2, so as not to interfere with the driving of the wedge by the hammer.

65 It will be observed that if the wedge car-

rier 19 is at the outer end of the double element 2 when the clamp is in position to be wedged into place, not only will the carrier 19 be out of the way when the single bar 6 is inserted through the double bars 7-8 and will not interfere therewith, but also it will be outside of the space enclosed by the clamp, and it will require no attention on the part of the operator to keep the wedges or chains or the carrier 19 itself from confusing the assembling operation. Furthermore, when it is desired to drive the wedges into the perforations, they will be convenient to the hand of the operator.

By providing rings 21 of sufficient diameter, the carrier 19 may be trapped permanently in the space between the bars 7 and 8. In this connection, it is an essential feature of my invention that the carrier 19 be made of suitable length between the links 21. If the links 21 be too close together, the carrier will not slide to the end of the double element 2 as above referred to, but will be wedged by the engagement of the rings 21 on opposite sides of the bars 7 and 8.

The carrier 19 should be of such length that when the double element 2 is tipped out of vertical, and the carrier 19 slides downwardly by sliding engagement of the upper ring 21 with the bars 7 and 8, the lower ring 21 will be out of contact with the bars 7 and 8. This feature of my invention will be understood by reference to the above description taken in connection with Fig. 2 of the drawing.

Furthermore, by sliding the carrier 19 to the extreme end of the double element 2, the carrier 19 and the chains thereon, will be removed sufficiently not to interfere with the nesting of the single bar in the double bar for transportation purposes, as shown in Fig. 5.

As will be understood by providing double rows of staggered perforations, the clamp of my invention is not only adapted to rectangular column molds of various sizes, but also of various shapes; and also when used with any shape or size, the clamping force exerted by the clamps may be gradually increased to any desired amount by driving the wedges farther and farther into the perforations; and also by having staggered perforations in the bars, a perforation may be selected for the wedge in which it may come tight regardless of slight variations in the size or shape of the form.

When it is desired to remove the column clamp from the mold, the wedges may be driven upwardly by striking the lower ends thereof with a hammer and the parts removed in the reverse order to that above described, as will be understood.

My invention is not limited to the exact details of construction shown and described, since my invention may be embodied in other

and various structures without departing from the spirit thereof or sacrificing its advantages.

I claim:

5. 1. In a clamp for molds or the like, a pair of clamp units, each unit comprising a pair of bar elements pivotally connected together at one end, one of the bar elements being composed from a flat rectangular bar and being provided with a longitudinally ranging series of staggered successively overlapping perforations, the other bar element being composed from a pair of similar flat rectangular bars spaced apart, the said single bar being interposed between the pair of bars at the pivot connection, a spacer between the pair of bars at the end opposite the pivot connection and rigidly connected to the bars and a longitudinally ranging series of staggered successively overlapping perforations in the pair of bars, the perforations in one bar being aligned with the corresponding perforations in the other bar, the single bar of one unit being adapted to be inserted through between the two bars of the other unit. 70
10. 2. In a clamp device unit for molds or the like, a pair of bar elements pivotally connected together at one end, one of the bar elements comprising a single bar and provided with a plurality of longitudinally disposed staggered successively overlapping perforations, the other bar element comprising a pair of bars rigidly connected together and spaced apart at their ends opposite the pivot connection and provided with a plurality of staggered successively overlapping perforations, the perforations of one bar of the pair being aligned with corresponding perforations in the other bar of the pair. 75
15. 3. In a clamp device for molds or the like, a pair of clamp units, each unit comprising a pair of bars pivoted together at one end, one of the bars comprising a pair of longitudinal branches, each of the bars being provided with a series of staggered successively overlapping perforations, the branched bar having said perforations in both branches and the perforations in one branch registering with those of the other branch, the unbranched bar of each of the clamp units being adapted to be inserted between the branches of the branched bar of the other units whereby the two units may entirely enclose a mold or the like to be clamped, and the branches of each branched bar being connected together and spaced apart at their end opposite the pivot connection. 80
20. 4. In a clamp device unit for molds or the like, a pair of bar elements pivotally connected together at one end, one of the bar elements comprising two branches, and each of the bar elements being provided with a series of staggered perforations, the perforations in one of the branches of the branched bar element being aligned with the perforations in the other branch, a wedge carrier having a body portion disposed in the space between the two branches and freely movable therein, means for preventing removal of the body member, and a pair of wedges flexibly connected to said wedge carrier. 85
25. 5. In a clamp device unit for molds or the like, a pair of bar elements pivotally connected together at one end, one of the bar elements comprising two branches, and each of the bar elements being provided with a series of staggered perforations, the perforations in one of the branches of the branched bar element being aligned with the perforations in the other branch, the two said branches being connected together at the end of the bar element opposite the pivot, a wedge carrier comprising an elongated body member disposed transversely of the branched bar element in the space between the branches, and a pair of wedges flexibly connected to the body member. 90
30. 6. In a clamp device unit for molds or the like, a pair of bar elements pivotally connected together at one end, one of the bar elements comprising two branches, and each of the bar elements being provided with a series of staggered perforations, the perforations in one of the branches of the branched bar element being aligned with the perforations in the other branch, the two said branches being connected together at the end of the bar element opposite the pivot, a wedge carrier comprising an elongated body member disposed transversely of the branched bar element in the space between the branches, and a pair of wedges flexibly connected to the body member. 95
35. 7. In a clamp device unit for molds or the like, a pair of bar elements pivotally connected together at one end, one of the bar elements being composed from two flat rectangular bars, a spacing element between the bars at the ends opposite the pivot connection, the bars and spacing element being rigidly connected together, the other bar element being composed from a single flat rectangular bar interposed between the said pair of bars at the pivot connection, a longitudinally disposed series of staggered perforations in the single bar element and a longitudinally disposed series of staggered perforations in each of the two said bar portions, the perforations in one portion being aligned with corresponding perforations in the other portion, a wedge carrier comprising a body portion disposed transversely in the space between the two spaced bars, slidable longitudinally in said space, the ends of the body portion projecting out of the said space on each side of the spaced bars, means on each end of the body portion preventing the removal of the body portion from said space and a pair of wedges flexibly connected to the wedge carrier. 100
40. 8. In a clamp for molds or the like, a pair of clamp units, each unit comprising a pair of bar elements pivotally connected together at one end, one of the bar elements comprising two branches, and each of the bar elements being provided with a series of staggered perforations, the perforations in one of the branches of the branched bar element being aligned with the perforations in the other branch. 105
45. 9. In a clamp device unit for molds or the like, a pair of bar elements pivotally connected together at one end, one of the bar elements comprising two branches, and each of the bar elements being provided with a series of staggered perforations, the perforations in one of the branches of the branched bar element being aligned with the perforations in the other branch, a wedge carrier having a body portion disposed in the space between the two branches and freely movable therein, means for preventing removal of the body member, and a pair of wedges flexibly connected to said wedge carrier. 110
50. 10. In a clamp device unit for molds or the like, a pair of bar elements pivotally connected together at one end, one of the bar elements comprising two branches, and each of the bar elements being provided with a series of staggered perforations, the perforations in one of the branches of the branched bar element being aligned with the perforations in the other branch, a wedge carrier having a body portion disposed in the space between the two branches and freely movable therein, means for preventing removal of the body member, and a pair of wedges flexibly connected to said wedge carrier. 115
55. 11. In a clamp device unit for molds or the like, a pair of bar elements pivotally connected together at one end, one of the bar elements comprising two branches, and each of the bar elements being provided with a series of staggered perforations, the perforations in one of the branches of the branched bar element being aligned with the perforations in the other branch, a wedge carrier having a body portion disposed in the space between the two branches and freely movable therein, means for preventing removal of the body member, and a pair of wedges flexibly connected to said wedge carrier. 120
60. 12. In a clamp device unit for molds or the like, a pair of bar elements pivotally connected together at one end, one of the bar elements comprising two branches, and each of the bar elements being provided with a series of staggered perforations, the perforations in one of the branches of the branched bar element being aligned with the perforations in the other branch, a wedge carrier having a body portion disposed in the space between the two branches and freely movable therein, means for preventing removal of the body member, and a pair of wedges flexibly connected to said wedge carrier. 125
65. 13. In a clamp for molds or the like, a pair of clamp units, each unit comprising a pair of bar elements pivotally connected together at one end, one of the bar elements comprising two branches, and each of the bar elements being provided with a series of staggered perforations, the perforations in one of the branches of the branched bar element being aligned with the perforations in the other branch. 130

- bar elements pivotally connected together at one end, one of the bar elements being composed from a flat rectangular bar and being provided with a longitudinally ranging series of perforations, the other bar element being composed from a pair of similar flat rectangular bars spaced apart, the said single bar being interposed between the pair of bars at the pivot connection, a spacer between the pair of bars at the end opposite the pivot connection and rigidly connected to the bars and a longitudinally ranging series of staggered perforations in the pair of bars, the perforations in one bar being aligned with the corresponding perforations in the other bar, the single bar of one unit being adapted to be inserted through between the two bars of the other unit, a wedge carrier associated with each of the bar elements composed of spaced bars, each wedge carrier comprising a body portion disposed transversely in the space between the two spaced bars, slideable longitudinally in said space, the ends of the body portion projecting out of the said space on each side of the spaced bars, means on each end of the body portion preventing the removal of the body portion from said space and a pair of wedges flexibly connected to the wedge carrier.
- 30 9. In a clamp device unit for molds or the like, a pair of bar elements pivotally connected together at one end, one of the bar elements comprising two branches and each of the bar elements being provided with a series of staggered perforations, the perforations in one of the branches of the branched bar elements being aligned with those in the other branch, and a pair of wedges either of which is adapted to be inserted through a pair of said aligned perforations and flexibly connected to the branched bar by connecting means movable longitudinally on the bar.
- 45 10. In a clamp device unit for molds or the like, a pair of bar elements pivotally connected together at one end, one of the bar elements comprising two branches and each of the bar elements being provided with a series of staggered perforations, a pair of wedges and a flexible connection between the wedges extending between the branches of the branched bar and slideable longitudinally therein.
- 55 11. In a clamp device unit for molds or the like, a pair of bar elements pivotally connected together at one end, one of the bar elements comprising a single bar provided with a plurality of longitudinally disposed staggered successively overlapping perforations, the other bar element comprising a pair of bar portions embracing therethrough a slot extending transversely therethrough and longitudinally over a portion of the bar length and provided with a plurality of staggered successively overlapping perforations,

the perforations of one bar portion being aligned with corresponding perforations in the other bar portion.

12. In a clamp device for molds or the like, a pair of clamp units, each unit comprising a pair of bars pivotally connected together at one end, one of the bars being provided with a longitudinally extending slot and each of the bars being provided with a longitudinally disposed series of staggered overlapping perforations, the unslotted bar of each unit being adapted to be inserted through a slotted bar of the other unit to entirely enclose the mold to be clamped, and a wedge adapted to be driven into a perforation of each unslotted bar to wedgily engage a portion of the slotted bar and a wedge adapted to be driven into a perforation of each slotted bar to wedgily engage a portion of each unslotted bar to constrictingly clamp the mold enclosed within the device.

13. In a clamp device for molds or the like, a pair of clamp units, each unit comprising a pair of bars pivotally connected together at one end, one of the bars of each unit being provided with a longitudinal slot therein, each of the unslotted bars being provided with a longitudinally ranging series of staggered successively overlapping perforations, and the slotted bars being provided each with two longitudinally ranging series of aligned staggered successively overlapping perforations, the unslotted bar of each unit being adapted to be inserted through a slotted bar of the other unit to thus entirely enclose a mold to be clamped, a wedge for each unslotted bar adapted to be driven through a perforation thereof to wedgily engage a portion of the slotted bar through which the unslotted bar is inserted and a wedge for each slotted bar adapted to be driven through a pair of aligned perforations thereof to wedgily engage a portion of the unslotted bar inserted through it to constrictingly clamp the mold enclosed within the device.

14. In a clamp device for molds or the like, a pair of clamp units, each unit comprising a pair of bars pivotally connected together at one end, one of the bars being provided with a longitudinally extending slot, the unslotted bar of each unit being adapted to be inserted through a slotted bar of the other unit to entirely enclose the mold to be clamped, each of the bars being formed to provide a longitudinally disposed series of spaced staggered abutments, and a wedge adapted to be wedgily driven between an abutment of each unslotted bar and a portion of the slotted bar and a wedge adapted to be wedgily driven between an abutment of each slotted bar and a portion of the unslotted bar to constrictingly clamp the mold enclosed within the device.

15. In a clamp device for molds or the like, a pair of clamp units, each unit comprising a

pair of bars pivotally connected together at one end, one of the bars being provided with a longitudinally extending slot, the unslotted bar of each unit being adapted to be inserted through a slotted bar of the other unit to entirely enclose the mold to be clamped, each of the bars being formed to provide a longitudinally disposed series of spaced staggered abutments, and a wedge adapted to be wedgely driven between an abutment of each unslotted bar and a portion of the slotted bar and a wedge adapted to be wedgely driven between an abutment of each slotted bar and a portion of the unslotted bar to constrictingly clamp the mold enclosed within the device, and the abutments of the slotted bar being disposed in aligned pairs, the abutments of each pair being on opposite sides of the slot.

16. In a clamp device for molds or the like, a pair of clamp units, each unit comprising a pair of bars pivotally connected together at one end, one of the bars being provided with a longitudinally extending slot, the unslotted bar of each unit being adapted to be inserted through a slotted bar of the other unit to entirely enclose the mold to be clamped, each of the bars being formed to provide a longitudinally disposed series of spaced staggered abutments, and a wedge adapted to be wedgely driven between an abutment of each unslotted bar and a portion of the slotted bar and a wedge adapted to be wedgely driven between an abutment of each slotted bar and a portion of the unslotted bar to constrictingly clamp the mold enclosed within the device, and a wedge when wedgely engaging one abutment of a bar being adapted to overlap the next adjacent staggered abutment of that bar.

17. In a clamp device for molds or the like, a pair of clamp units, each unit comprising a pair of bars pivoted together at one end, one of the bars being provided with a longitudinal slot extending transversely therethrough and each of the bars being provided with a longitudinally ranging series of wedge-receiving perforations, the unslotted bar of each unit being adapted to be inserted through a slotted pair of the other unit to entirely enclose the mold to be clamped, and a pair of wedges associated with the slotted bar and connected together by a flexible connection extending through the slot.

18. In a clamp device for molds or the like, a pair of clamp units, each unit comprising a pair of bars pivoted together at one end, one of the bars being provided with a longitudinal slot extending transversely therethrough and each of the bars being provided with a longitudinally ranging series of wedge-receiving perforations, the unslotted bar of each unit being adapted to be inserted through a slotted pair of the other unit to entirely enclose the mold to be clamped, and

a pair of wedges associated with the slotted bar and connected thereto by a flexible connection slidable longitudinally of the said slotted bar.

In testimony whereof I hereunto affix my ⁷⁰ signature this 30th day of October, 1929.

RALPH R. ROEMER.
